[57] ABSTRACT

The liquid phase coking of waste alkaline sulfite pulp liquors can be effected at a faster rate and a lower temperatures by lowering the pH of such liquors by at least one pH unit. Also desirably, both the coke yield is increased and the Chemical Oxygen Demand of the resulting effluent is lowered. The pH lowering is achieved by adding sulfur dioxide to the waste liquor either as free SO_2 or a water solution of SO_2 . The effluent and the chemicals recovered after coking can be recycled in the paper pulp process from which they were recovered.

COKING OF WASTE ALKALINE SULFITE PULP LIQUOR AT LOWERED PH

BACKGROUND OF THE INVENTION

1. Field of the Invention

The present invention relates to an improved process for treating waste alkaline sulfite pulp process liquor containing organic matter dissolved from wood.

2. Description of the Prior Art

In the production of pulp and paper, wood is treated with chemicals to remove lignin binder from the cellulose fibers of the wood. In the process, about one-half the dry weight of the tree processed is dissolved in the pulping liquor and only about half recovered as pulp that is subsequently processed to useful paper products. The soluble portion, most of which is discarded as waste in the sulfite pulping process, presents a serious disposal problem. According to recent reports in the trade literature, sulfite liquor from over 100 pulp mills in the United States and Canada is disposed of by pumping the waste liquor into the nearest river or other body of water. Legislation in many states now prohibits the discharge of sulfite waste liquor into streams, resulting in efforts by mills to find the best method of utilizing or disposing of the waste liquor.

Acid cooking liquor for the sulfite process is usually prepared by the reaction between sulfur dioxide and limestone in the presence of water forming calcium bisulfite $\text{Ca}(\text{HSO}_3)_2$. Instead of limestone, which forms a calcium based sulfite acid liquor, the acid cooking liquor may be prepared from ammonium carbonate, ammonium hydroxide, magnesium carbonate, magnesium hydroxide, or the carbonate, bicarbonate, sulfite or hydroxide of sodium.

The reactions which take place in the cooking process involve formation of an ammonium or alkali metal salt of lignin sulfonic acid which is soluble and is dissolved out of cellulose in the cooking process. Sufficient metallic ion (or alternatively the ammonium ion) to form the salt of lignin sulfonic acid must be present in the cooking process to produce high yield of pulp.

Heretofore, however, it has not been possible with sulfite pulps to obtain strength and other desirable properties equal to those of sulfate or kraft pulps produced by cooking pulp in a solution of sodium hydroxide and sodium sulfide. Important objections to the kraft process has always been the complicated recovery system and the offensive odors released owing to the production of mercaptans.

Lately, a new process has been found which compares favorably with the kraft process and operates in a sulfide-free alkaline sulfite liquor in which the alkalinity is maintained throughout the cook at about between pH 8 and pH 11 as measured in situ at the cooking temperature, the pH being maintained within these limits by the addition of a strong base. This process is described in Canadian patent No. 847,218 issued on July 21, 1970 to O. V. Ingruber et al. and assigned to Canadian International Paper Company. As pointed out in the Aug. 24, 1970 edition of *Chemical Week* at page 31, it does not appear that this process includes an adequate chemicals recovery system. A possible reason for this lack may be the strong basic character of the waste sulfite liquor. Indeed attempts to treat this waste liquor by coking according to the method of commonly assigned U.S. Pat. No. 3,507,788 indicated that the rate of coke formation was slow.

SUMMARY OF THE INVENTION

Unexpectedly it has been discovered that lowering the pH of the waste alkaline sulfite liquors facilitates liquid phase coking of these liquors thereby providing an improved means of removing from the liquors dissolved lignins with an attendant recovery of chemicals. Lowering of pH is achieved by adding sulfur dioxide to the waste alkaline sulfite liquor to give at least one pH unit reduction.

DESCRIPTION OF SPECIFIC EMBODIMENTS

It has been found that any addition of sulfur dioxide to bring the waste alkaline sulfite liquor to a less alkaline condition prior to coking in the absence of air is beneficial. Thus if the pH of the liquor is from pH 8 to about pH 11 a pH reduction from pH 8 to pH 7 or pH 11 to pH 10 is advantageous insofar as coking and recovery of chemicals is concerned. However, the greater the reduction in pH, the greater the response of the waste to coking. Generally it is preferred to reduce the pH by at least one unit, e.g., 8 to 7 but it is better to reduce the pH of the waste alkaline sulfite liquor to within the range of pH 7 to pH 3.

25 The operating temperatures during the coking step will range from about 400°-700°F but preferably will be 450°-650°F.

The operating pressure is the autogeneous pressure of about 300-3,500 psig.

30 The coking time can vary from 0.5 minutes to two hours. Following coking the coke is separated by filtrations and the coke burned to provide process heat and a source of sulfur dioxide. Any gases formed are vented and preferably burned to provide an additional source of sulfur dioxide for recycle. The filtrate is recycled after being refortified and chemically adjusted to provide the alkaline sulfite pumping liquor.

35 The process of the invention can be carried out in apparatus similar to that described and shown in commonly assigned U.S. Pat. No. 3,507,788 except that the use of an oxidizer unit for oxidizing the effluent is not necessary. The apparatus can then consist mainly of a tubular heater of the type commonly used in the processing of petroleum wherein the temperature of the waste liquor is raised to the desired coking temperature at a pressure sufficient to prevent the vaporization of water. The hot waste liquor can then be introduced into a separator suitable for holding the heated waste liquor at the desired processing temperature and pressure. Gas released during coking is discharged from the separator through a relief valve. Coke settles from the aqueous liquid and collects in the lower part of the separator from which it is discharged through a valve into a flow tank. Aqueous effluent is withdrawn from the upper part of the separator and is reused in the pulping process. Where otherwise convenient, such as when the quantities of liquor are small, autoclaves may be used.

60 65 66 As shown in the accompanying graph, adding SO_2 to the waste liquor to lower its pH prior to coking, drastically reduces the Chemical Oxygen Demand (COD) of the coked effluent relative to a basic waste liquor for the same temperature, pressure and coking time. Thus coking a liquor having a pH of 1.9 for 110 minutes reduced its COD by 80 percent while coking another sample having a pH of 12 at the same temperature and pressure for the same time only reduced the COD by

58 percent. This difference is all the more important since huge volumes of waste liquor are generally treated in paper making plants.

That coking is facilitated by the practice of the present invention was evidenced by the observation that lignins could be coked at a lower temperature. In addition, a light straw-colored liquid recycle was obtained when the pH of the liquor was reduced whereas a dark colored recycle liquor was obtained when the alkaline liquor was coked in the basic state.

It will be appreciated that the present invention is applicable to all alkaline sulfite-containing liquid wastes

quor, pH 12 of Example I. These are presented as Example II through V in Table I, below. In all the runs coking was done at 550°F with coking times varying from five minutes to 120 minutes. It will be noted that as the result of coking 5 minutes, 0.42 parts by weight of dry coke was recovered and the filtrate had the high COD value of 101,429 mgO₂/l relative to the charge COD of 146,734 mgO₂/l. Coking for successively longer times resulted in the separation of increasing amounts of coke with an attendant decrease in COD, i.e., from a value 101,429 after 1 minute to 56,918 after 2 hours.

regardless of their origin and is not limited to those obtained as a result of practicing the process of Canadian Pat. No. 847,218.

The examples given below are presented to illustrate more clearly the nature of the present invention. It should be noted, however, that the invention is not limited to the embodiments given in the examples.

EXAMPLE I (Analysis of Feed Waste Liquor)

The analyses on the alkaline sulfite liquor are as follows:

Sample No.	70-4032
Sulfur, wt %	1.40
Sodium, wt %	3.37
Calcium, wt %	0.007
Carbon, wt %	5.4
Nitrogen, wt %	0.0001
COD, mgO ₂ /l	146,734
Na ₂ SO ₃ %	4.9
pH	12

EXAMPLES II - V

The alkaline sulfite liquor is coked at 550°F under autogeneous pressure in batch bombs for various lengths of time using a high tin metal bath as the heat transfer medium. After the designated reaction time, the tube or bomb is withdrawn, cooled and the contents filtered to separate the coke from the filtrate. The wet filter cake is dried.

Four runs were made with the Alkaline Sulfite Li-

EXAMPLES VI - VIII

(Coking of sulfite liquor with pH lowered by adding SO₂)

Examples VI-VIII as summarized in Table II below, show the comparative effect of adding SO₂ to the alkaline sulfite liquor.

Thus in Example VI, 5.5 parts by weight of SO₂ was added to 54.5 parts by weight of the alkaline sulfite liquor to change the pH from 12 to 3. This addition represented about a 50 percent excess over that required to neutralize the excess base in the waste liquor. The liquor was then coked at 550°F for 5 minutes and the product cooled. The cooled product was filtered to give 3.0 parts of dry coke and a filtrate having a COD of 43,654. This result is to be compared directly with the results of Example II. Thus by adding SO₂, $3.0 - 0.42/0.42 \times 100 = 612$ percent more coke was obtained and the COD was reduced to 43,654 mgO₂/L compared to a COD of 101,429 mgO₂/l without the use of SO₂. These very substantial advantages obtained in employing SO₂ were accompanied by an improved filtrate color, that is, when coking was done without the use of SO₂, the color was black whereas when SO₂ was added prior to coking the filtrate color was light yellow.

Examples V and VII provide another direct comparison of the effectiveness of employing added SO₂ in the coking of the alkaline sulfite liquor. No SO₂ was added in Example V while in Example VII 5.5 parts of SO₂ was added to 54.5 parts of liquor thereby giving about 50 percent over the amount needed to neutralize the free base in the waste liquor. Coking was done in both runs at 550°F for 2 hours.

⁽¹⁾Loss due to foaming.

Without the use of added SO₂, 2.34 parts by weight of dry coke was secured and the COD was reduced to 56,918 mgO₂/l whereas with added SO₂, 2.8 parts by weight of dry coke was recovered and the COD was reduced to 21,877 mgO₂/l. Coking in the presence of added SO₂ resulted in a light yellow filtrate whereas in the absence of SO₂ the filtrate from the coking step was blank.

Example VIII was similar to Example VI with the exception that less SO₂ was added to the waste alkaline sulfite liquor. That is, 3.5 parts by weight of SO₂ was added to 56.5 parts by weight of waste liquor, or about 5.6 percent less than is theoretically required to neutralize the excess NaOH present. Coking at 550°F for 5 minutes resulted in 2.9 parts by weight of dry coke being recovered, and a dark filtrate having a COD of 48,595 mgO₂/l. The pH of 8 of the filtrate reflects the lower amount of SO₂ charged. The experiment teaches

that even though less SO₂ was added to the waste liquor than that required for neutralizing the caustic, coking was made more effective than when SO₂ was not added, however, it was less effective than when a surplus over that required to neutralize the base was used. Additionally, a lower concentration of sodium in the coke was found when operating with a large surplus of SO₂. These facts are set forth as follows:

Example SO ₂ added	II	VI	VIII
	None	53% excess	5.6% less than required for neutralization

EXAMPLES IX-XI

EFFECT OF VARYING AMOUNTS OF ADDED SO₂

Examples IX-XI as summarized in Table III show additional data on the effect of adding SO₂ to the alkaline sulfite liquor. These examples differ from the earlier examples as follows:

a. In Example IX, SO₂ was added to the sulfite liquor to give a feed having a pH of 5, the coking was done at 500°F and the filter cake was washed with water to remove sodium.

b. In Example X, the procedure in Example IX was repeated excepting coking was done at 550°F. It will be noted that a filtrate having a lower COD was obtained as the result of coking at 550°F, i.e., 48,947 MgO₂/l vs 56,748 mgO₂/l secured at 500°F.

c. In Example XI, SO₂ was added to the sulfite liquor to give a feed having a pH of 4, coking was done at 550°F and the coke was washed to remove sodium.

EXAMPLE XII

FIG. 1 shows in graph form the dramatic effect of adding sulfur dioxide to the waste alkaline sulfite liquor on its response to coking with subsequent removal of coked lignins. Thus upon coking an original waste liquor for 20 minutes about 30 percent reduction in COD was achieved, whereas with the same liquor made acid, pH 1.9, with sulfur dioxide the COD reduction was about 71 percent.

To avoid gel formation it is preferred to heat rapidly

to the coking temperature at least in the range of 350° to 500°F. As described and claimed in our copending application Ser. No. 149,673, now abandoned, filed even day herewith, this heating rate can be about 110°F to 150°F per minute in the temperature interval of about 350°F to 550°F.

We claim:

- 30 1. In a process for treating alkaline sulfite waste pulping liquors having a pH in the range of pH 11 to pH 8 by coking said liquors in the liquid phase at temperature ranges from about 400° to about 700°F, at a pressure of about 300 to 3,500 psig for a coking time in the range of about 0.5 minutes to about 2 hours to form coke, exhaust gases and an aqueous effluent; separating said coke from said effluent; and recovering said effluent to form additional pulping liquor, the improvement consisting of lowering the pH of said liquors by at least one unit by the addition of extraneous SO₂ before coking same, and burning said coke and said exhaust gases to recover chemical values therefrom for recycling.
- 35 2. The process according to claim 1, wherein an excess of SO₂ is added over and above that required to neutralize the caustic present in said liquors.
- 40 3. The process according to claim 1, wherein coking is carried out at between 450° to 650°F.
- 45 4. The process according to claim 1, wherein the pH of the liquor is reduced to within the range of pH 7 to pH 3 prior to coking.
- 50 5. The process of claim 1, wherein the pH of the liquor is reduced to 1.9 before coking.
